UNITED STATES PATENT OFFICE.

WILLIAM H. HOPE, OF PROVIDENCE, RHODE ISLAND.

METHOD OF ENGRAVING COPPER ROLLS FOR PRINTING FABRICS.

1,259,986.

Specification of Letters Patent. Patented Mar. 19, 1918.

Application filed June 4, 1917. Serial No. 172,607.

To all whom it may concern:

Be it known that I, WILLIAM H. HOPE, a citizen of the United States, residing at Providence, in the county of Providence and State of Rhode Island, have invented a new and useful Improvement in Methods of Engraving Copper Rolls for Printing Fabrics, of which the following is a specification.

This invention relates to certain new and useful improvements in the method of engraving copper rolls for printing fabrics, and more particularly to the transferring of the design by a stylus and cutter or graver proportionate in size to the desired width of undercut produced on the roll by the acid etching.

The invention primarily resides in the method of engraving by a stylus having a flat edge instead of the usual pointed tool, said flat edge being proportionate in size to the desired width of the undercut that is to be produced by the acid etching, and a graver also having an edge of such width as is necessary for the removal of the varnish from the roll to permit of the action of the acid on said copper roll for causing the proper undercut.

The invention will be better understood by reference to the accompanying drawing 30 wherein—

Figure 1 illustrates a design shown in the colors desired on a flat sheet metal plate, usually and preferably zinc.

Fig. 2 is a fragmentary portion of a copper roll showing a portion of the brown color part of the design engraved thereon.

Fig. 3 is a similar view of a roll bearing the blue color part of the design.

Fig. 4 is a view of a roll having a portion of the red color part of the design engraved thereon.

Fig. 5 is an enlarged squared portion of any one of the colors shown by itself for ease in describing the method.

Fig. 6 illustrates the stylus diagrammatically.

Fig. 7 is a like illustration of the graver, and

Fig. 8 shows in solid lines the portion of 50 varnish removed from the copper roll by the graver in tracing the square shown in Fig. 5 with the stylus, the dotted portion of said Fig. 8 representing the extent of undercut of the acid in the etching process.

Referring more particularly to the drawing, the numeral 1 indicates either a portion

of a design or the complete design itself which is painted or otherwise indicated on a flat sheet metal plate, said plate preferably being zinc and said colors of the design 60 preferably being those in which the finished fabric will be printed. This plate, bearing the design, is ruled with a number of horizontal and perpendicular lines 1' to represent the desired mesh or block of the weave 65 to be reproduced, the drawing being divided into nine blocks to the inch although on an enlarged scale.

The usual method of engraving print rolls employs a pointed stylus but with such tool 70 or instrument it is impossible to determine the undercut of the acid etching. This invention embodies a flat edged stylus 2 and a like edged graver, the latter having an edge of such width as is necessary for the removal of the proper amount of varnish from the copper roll, dependent upon the amount or extent of undercut of the acid. Since the depth of etching depends upon the texture 75 that is to be printed and the character of 80 the color, and since the quantity of the acid governs the depth and undercut thereof, it is readily apparent that for a shallow etching a narrow stylus is required and for relative deep etching a comparatively wide or 85 broad stylus is necessitated. The degree of undercut is previously determined so that the required stylus may be selected, the width of the stylus being twice the amount of undercut. Therefore, should a graver be 90 positioned for moving in unison with the stylus and the latter be shifted laterally or edgewise from a position in which one side of said stylus touches one border line of a pattern to a position in which the opposite 95 side of the stylus touches the opposite border line, the total travel of the stylus will be the full width of the pattern less the width of the stylus edge. Consequently, the extent of movement of the graver will be 100 accordingly great, less the width of the stylus which provides for the necessary undercut of the etching fluid. To obtain the desired space at each end of the limit of operation of the graver, to accommodate for 105 the undercutting of the acid in both directions, it is essential that the latter be started at a point midway of the width of the stylus. For ease in relatively positioning the stylus and graver, the former is provided with a 110 center line (Fig. 6) and the graver may then be alined with the same so that the starting

and finishing points of the graver will be one-half the width of the stylus inwardly from the extreme reach of said stylus. Therefore, the acid undercut or etching will 5 be equal to one half the width of the stylus. The width of the face of the graver is equal to the width of the pattern transferred to the roll less twice the amount of the acid undercut in order to produce the same width 10 of border around the block design for acid under etching.

As illustrative of the present method, Fig. 5 represents a single square block of color of the design taken from the design plate 1. 15 The stylus is then placed on the top edge of the block of color with its edge 4 on the left hand border 5 of said block, and the graver 3 is dropped onto the roll 6 (Figs. 2, 3 and 4), care having been taken to set 20 the left edge of the graver on the left border of the particular design block. The stylus is moved along the top line to the broken line position 7, Fig. 6, or until the right edge 8 of the stylus registers with the right hand border of the square. This movement, 25 through the pantograph mechanism, effects movement of the graver moving the latter to the dotted position 9, Fig. 7. Thus referring to Figs. 5 and 8 with the edge of the 30 stylus being moved longitudinally along the upper line of block 5, the graver will move broadwise. The extent of movement required to shift the stylus from the position in which its left end touches the border of 35 square 5 to the position in which the right end touches the right border of said square is indicated by the top line of square 10 and a vertical side of the latter designates the width of the face of the graver. This operation 40 will remove varnish from the roll as indicated at 10, the difference in size between the square 10 and that shown in Fig. 5 being equal to the extent of undercut of the acid, this being indicated by the dotted 45 square 11. Consequently, should acid be applied to the roll, the undercut of the metal would be such as to produce a square as large as the dotted lines 11 or as large as that of Fig. 5.

50 A stylus and graver of proportionate size will be used, depending upon the fabric to be printed, to produce a depth of etching in the roll that will carry the proper amount of color for such printing. The width of 55 the stylus is always proportioned inversely to the width of the graver and as the action of the stylus is on the top edge of the color, the roll on which the graver operates will have the edge of the graver represent 60 the top line of the color, so that the wider the face of the graver, the narrower the face of the stylus will be and the greater the undercut. This relation between the width of 65 the face of the graver and that of the stylus is necessary in order to produce the same

width of border around the block design for acid under etching.

The rolls in Figs. 2, 3 and 4 represent individual rolls for each color, the roll for the brown color being depicted in Fig. 2, that for the blue color being shown in Fig. 3, and that for the red color being disclosed in Fig. 4. The colors, or their squares or configurations, are depicted before the application 75 of the etching acid so that said configurations correspond to the smaller square 10 in Fig. 8, being less than the true size.

Thus, by employing the stylus and graver proportionate to the undercut desired, which depends upon the fabric to be printed and the color to be carried by the roll, it will be unnecessary to constantly determine the extent of undercut; no expert help or operative 80 will be required, and the same unvarying and perfect blending of the colors with no irregular or overlapping edges will result.

In practice, the graver or cutter is set at right angles to the stylus and secured by its shank in a suitable holder, such as the usual diamond bar, and the stylus is mounted 90 in the hand piece that moves over the design or pattern.

Having thus described my invention, what I claim as new and desire to secure by Letters Patent is—

1. The method of engraving copper rolls for printing fabric, consisting in dividing the pattern into blocks of colors, providing a flat edged stylus and a graver having an edge of a width inversely proportionate to 100 the width of the stylus disposing the graver edge at right angles to the stylus edge, and moving the edge along the top line of a block of the pattern, engraving the individual colors on separate rolls.

2. The method of engraving rolls consisting in dividing the pattern into blocks of individual colors, providing a stylus and graver, each with a flat edge, arranging the graver edge at right angles to the stylus 110 edge, and moving the latter along a border line of a pattern block.

3. The method of engraving rolls consisting in dividing the pattern into blocks of individual colors, providing the stylus and graver each with a flat edge, the wider the stylus edge the narrower the graver edge, arranging the stylus and graver so that the latter will operate broadside on a roll on movement of the stylus edge longitudinally, and moving the stylus edge along a border line of a pattern block.

4. The method of engraving rolls consisting in tracing edgewise a flat edge stylus equal in width to twice the amount of the 125 undercutting of the acid, and moving a flat edge graver broadwise.

5. The method of engraving rolls, consisting in tracing a border line of a pattern with a stylus having an edge equal to dou- 130

ble the width of the undercut of the acid, providing a graver equal in width to the design less twice the undercut, and moving the stylus edgewise and the graver broad-

5 wise.

6. The method of engraving consisting in tracing the border of a color with a stylus having a width equal to twice the amount of the underetching and moving a graver

10 broadwise, said graver being equal in width

to the design less twice the amount of the underetching.

In testimony whereof I have signed my name to this specification in the presence of two subscribing witnesses.

WILLIAM H. HOPE.
